FOREIGN PATENT DOCUMENTS

GB 222052 A 9/1924

Primary Examiner — Darlington Ly(74) *Attorney, Agent, or Firm* — Chirstensen O'Connor
Johnson Kindness PLLC(57) **CLAIM**

The ornamental design for a mud flap, as shown and described.

DESCRIPTION

FIG. 1 is a top, rear, and left side isometric view of a mud flap showing my new design;

FIG. 2 is a bottom, front, and right side isometric view thereof;

FIG. 3 is a rear elevation view thereof;

FIG. 4 is a front elevation view thereof;

FIG. 5 is a top plan view thereof;

FIG. 6 is a bottom plan view thereof;

FIG. 7 is a right side elevation view thereof; and,

FIG. 8 is a left side elevation view thereof.

The broken lines in the drawings illustrate portions of the mud flap that form no part of the claimed design.

1 Claim, 6 Drawing Sheets(56)
